DEFENSIVE PUBLICATION

UNITED STATES PATENT AND TRADEMARK OFFICE

Published at the request of the applicant or owner in accordance with the Notice of Dec. 16, 1969, 369 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

U.S. Cl. 444—1

25 Sheets Drawing, 76 Pages Specification

A data processing system having an architecture in which all functions are conducted employing a method of virtual memory addressing, including all input and output functions. Any use of memory by the system, whether for data, program, workspace, etc., is by virtual address, requiring translation to a real address. The sole function employing real addresses is a virtual memory paging operation which is separate from all other input/output functions. In this manner, the system considers all programming and all data to be located in a large virtual memory but which are actually paged into a real main memory as needed.
